UNITED STATES PATENT OFFICE.

CLARENCE E. STELTZ, OF MILWAUKEE, WISCONSIN.

VENTILATING WINDOW LOCK.

1,403,207.

Specification of Letters Patent. Patented Jan. 10, 1922.

Application filed April 26, 1921. Serial No. 464,584.

To all whom it may concern:

Be it known that I, CLARENCE E. STELTZ, a citizen of the United States, and resident of Milwaukee, in the county of Milwaukee, 5 and State of Wisconsin, have invented certain new and useful Improvements in Ventilating Window Locks; and I do hereby declare that the following is a full, clear, and exact description thereof.

10 My invention has for its object to provide a simple, economical and positive means for locking partially opened windows or the like, whereby ventilation can be had, while at the time the windows cannot be 15 further opened for the purpose of entry therethrough by burglars.

A further object of the invention is to provide means for opening the windows at predetermined distances, whereby the 20 ventilation can be increased or diminished.

A still further object is to provide a locking means which can readily be dismantled from the windows when not in use.

With the above and other objects in view, 25 the invention consists in certain peculiarities of construction and combination of parts, as are hereinafter set forth with reference to the accompanying drawings and subsequently claimed.

30 In the drawings:

Figure 1 represents a side elevation of a fragment of upper and lower window sashes, having attached thereto a locking means embodying the features of my invention, parts being in section as indicated by 35 line 1—1 of Figure 2.

Figure 2 is a face view of the same with parts broken away and in section.

Figure 3 is a detail cross-section of a 40 locking gear, the section being indicated by 3—3 of Figure 1.

Figure 4 is a detail plan sectional view of the locking mechanism, the section being indicated by 4—4 of Figure 1, and

45 Figure 5 is a detail plan view of a locking saddle attachment.

Referring by characters to the drawings, 1 represents a right angle bracket that is secured to the lower rail of the upper sash, 50 the bracket being provided with an elongated receiving slot 2 and a locking notch 2'. The bracket has fitted thereto a metallic strap 3, having companion spaced pairs of notches 3' throughout its length. The bottom of the bracket is formed with an in-

turned foot 4, having a reduced shank portion adapted to slide within the slot 2. The strap is assembled in connection with the bracket 1 by turning the same at a right angle to its normal position, whereby the 60 foot 4 will enter the slot 2 and the strap is thereafter twisted upwardly to a vertical position, as shown in Figure 2, whereby the slotted connection between it and the bracket will lock the parts together. The 65 strap is held against vertical swing by means of a lug 5, which lug enters the notch 2' of the bracket.

The upper rail of the lower sash has secured thereto an upwardly bowed bracket 6, the bowed portion of which is formed with a longitudinally disposed narrow slot 7 for interlocking engagement with a T-shaped end 8 of a key member 8'. The shank of this key member is of such width 75 as to also permit it to engage a slot 9 of a locking saddle 9'. The locking saddle is formed with downturned feet for nested engagement with the upset side walls of the bowed bracket 6, and the projecting end of 80 the locking saddle is formed with an elongated slot 10, whereby the strap may be freely moved up and down with relation to the saddle for adjustment. After such movement, the strap is given a quarter turn, 85 whereby its companion notches 3' will engage the upper and lower surface of the locking saddle body, and thus prevent movement of the saddle with relation to said strap. Hence, when the saddle has been 90 locked in a selected set of the strap notches, the windows are moved so as to cause the saddle to drop over the head of the key 8', and thereafter said key is turned to the 95 position shown in Figure 1, whereby the saddle is securely locked to the upper rail of the lower sash. Hence, the upper and lower sashes are now firmly connected by the strap so that should they be shifted in their cases, they will move together and the 100 distance between the windows which permit ventilation cannot be changed from the outside.

In some instances, I may desire to provide a safety clip 11, which safety clip is provided with a slot whereby it can be adjusted up and down the strap 3, and the opposite end of the clip is provided with a slot transversely disposed with relation to the first mentioned slot, whereby said 110

clip can be dropped over the head of the locking key 8' and will thus prevent the same from being turned by a wire or other means introduced between the windows from the outside. Hence, it will be seen that a very simple and inexpensive device is produced, which can be attached to the rails of a window readily, and which can be dismantled without the aid of a screw driver 10 when it is desired to remove said device.

It is understood that I may vary the structural features of the safety lock without departing from the spirit of the invention.

15 I claim:

1. A ventilating device for windows comprising a bracket attachable to the rail of a window, a strap extending therefrom having notched edges, a bowed bracket adapted 20 to be secured to the rail of a companion window, having a slot therein, a locking saddle having a slot engageable with selective pairs of the strap notches, the locking saddle being provided with a transversely disposed slot in alignment with the bowed bracket slot, and a revoluble key extending 25

through the slots for locking the bowed bracket and saddle together.

2. A ventilating device for windows comprising a bracket attachable to the rail of a window, a strap in key connection with the bracket, the strap having its edges provided with a series of spaced pairs of notches, a bowed bracket having a slot therein secured to the companion window rail, a locking saddle having a slot for adjustable locking engagement with the notches of the strap, the locking saddle being provided with a second slot arranged transversely with relation to the first mentioned slot, a revoluble key for engagement with the last mentioned saddle slot and bowed bracket slot, whereby the said parts are locked together and a safety clip in slidable engagement with the strap for locking engagement with the key. 45

In testimony that I claim the foregoing I have hereunto set my hand at Milwaukee, in the county of Milwaukee and State of Wisconsin.

CLARENCE E. STELTZ.
